TO THE SHARPE MANUFACTURING CO., OF LOS ANGELES, CALIFORNIA, A CORPO-
RATION OF DELAWARE

AIR COMPRESSOR

Application filed January 26, 1927. Serial No. 163,721.

This invention relates to air compressors, and particularly to the piston type. Fluid compressors of this type of course are now in general use for such purposes as paint spraying or refrigeration. In many instances these compressors have inlet and outlet valves of the usual puppet form—that is, spring pressed to closed position, and opened in accordance with the conditions of fluid pressure existing in the cylinder controlled thereby. The efficiency of such compressors depends somewhat upon the structure of these valves, the optimum condition being one in which the valves open rapidly to permit a fast flow of fluid into and out of the cylinder. Such large openings are also essential to prevent "wire drawing" as well as clogging, which may easily occur when the compressor is used for such purposes as paint spraying. Under such circumstances paint particles (which exhibit tenacious tendencies) may stick to the intake openings, and if these openings are small, may be retained therein and interfere with the efficient operation of the apparatus. It is one of the objects of my invention to overcome these disadvantages by proper structure of the valves.

Considering the outlet or discharge valves, it has been common to utilize a valve closure that fits rather snugly into a valve pocket and that is urged into place by a spring. Upon sufficient pressure being developed in the cylinder, the closure is lifted, and compressed air is allowed to escape into a receiving chamber. To permit the escape of air past the closure, it has been common to provide grooves or the like therein. Such a structure is expensive, and with the aid of my invention, is obviated. In its place I substitute a valve closure that serves also as a spring seat and that can be simply constructed from standard material, such as square or hexagon rods.

It is still another object of my invention to provide a compact valve structure for a multiple cylinder device that is entirely enclosed except for a screened inlet opening, whereby dirt or foreign matter is prevented from finding its way into the compressor cylinders.

It is still another object of my invention to

improve in general, compressors of this character.

It is still another object of my invention to provide a compact and totally enclosed gear drive for the compressor. 55

My invention possesses many other advantages, and has other objects which may be made more easily apparent from a consideration of one embodiment of my invention. For this purpose I have shown a form in the drawings accompanying and forming part of the present specification. I shall now proceed to describe this form in detail, which illustrates the general principles of my invention; but it is to be understood that this detailed description is not to be taken in a limiting sense, since the scope of my invention is best defined by the appended claims. 60 65

Referring to the drawings:

Figure 1 is a side elevation of a compressor embodying my invention; 70

Fig. 2 is a plan view of the head structure, as seen from arrow 2 in Fig. 1;

Fig. 3 is a similar view but with cover removed, exposing the valve parts, the view being taken along plane 3—3 of Fig. 1; 75

Fig. 4 is an enlarged sectional view taken along plane 4—4 of Fig. 3, but with the cover shown as in place;

Fig. 5 is an enlarged elevation, partly in section, of the gear casing used in connection with my compressor; and 80

Fig. 6 is a detail section of the inlet nozzle for the compressor.

In the present instance I show a four cylinder structure, including a casing 11 that houses the usual operating parts of the compressor, and from which projects a cylinder block 12. This block is shown as having a series of horizontal radiating fins 13 extending completely around the block 12. Gearing 14 (Fig. 5) is encased at one side of the casing 11 and serves as a transmitter of motion from a shaft 15 that carries a flexible shaft coupling structure 16. 85 90 95

The gearing 14 is housed in the extending portion 17 of casing 11, which has a cover 18 clamped over portion 17 as by cap screws 19. The driving shaft 15 has a long bearing member 20 cast integral with cover 18, and car- 100

ries at its inner end, the driving pinion that forms one element of gearing 14. This gear casing structure is compact, and simple to manufacture, and provides a bearing support in a convenient manner, for the shaft that serves to drive the crank shaft 21.

The upper end of cylinder block 12 carries the cylinder closure and valve structure 22, whereby the cylinder bores 23 are covered, and whereby the valve structures are supported. This structure is shown in this instance as substantially rectangular, and as having outside walls 24 and 25 as well as an intermediate wall 26, dividing it into two compartments 27 and 28. Compartment 27 accommodates the inlet valves 29, and compartment 28 accommodates the outlet valves 30. The details of the valve structures will be set forth at length hereinafter. It is sufficient for the present to state that these valves are paired, one inlet and one outlet valve for each cylinder, but separated by wall 26.

An air tight cover plate 31 fits over the valve plate 22 and entirely covers both compartments 27 and 28. A series of radiating fins 32 is shown as cast integrally with the cover for maintaining this portion of the compressor cool, and cap screws 33 can be used, passing through the cover 31 and structure 22 for tightly holding these parts to the cylinder block 12.

In order to permit the compressor to "breathe" in spite of the covering thus provided, there is an intake nipple 34 that screws into the wall of structure 22. The nipple has screwed over it, a threaded extension 35 (Fig. 6) which in turn accommodates a hexagon nut 36. A screen 37, preferably of fine copper or brass, is clamped between an internal shoulder 38 of nut 36, and the contiguous end of the pipe extension 35. In this way, it is assured that no large particle of dust or dirt can find its way into the cylinders through the valve structure.

The valve structures are most clearly illustrated in Fig. 4. The inlet valve includes a sloping or tapered seat 39, defining an opening into bore 23, and on which is normally seated the valve closure member 40. This opening leads into the straight aperture 42. A valve stem 43 is slidable in the overhanging portions 41 of the valve aperture 42, which portions define in this instance three arcuate openings 44 that serve to permit air to enter into the aperture 42, and thence around the valve closure 40, whenever the suction in the cylinder is sufficient to unseat the valve closure, in a manner now well understood. The valve closure is urged to closed position by the aid of a compression spring 45 surrounding stem 43, and resting on the portions 41, and abutting at its upper end, a flanged washer 46 that is confined against outward movement by pin 47 passing through the stem 43. It is evident that,

due to this structure, large opening are exposed through which air can flow into the cylinders.

The outlet valve structure is also shown clearly in Fig. 4. It operates to uncover an opening in response to the creation of sufficient pressure in the cylinder and to pass the compressed air or fluid into the compartment 28, whence it is conducted through the outlet aperture 48 to a storage place or to a locality where it is to be used. The outlet valve seat 49 is also tapered, and a straight bore 50 leads into it, this bore being quite deep and serving as a guide for the valve closure 51.

This valve closure has a tapered extremity seating upon the seat 49, and is hollow to serve as a spring pocket for the compression spring 52 which urges the valve to closed position. The upper end of spring 52 is confined by the lower surface of the cover. The cover also has spaces such as 53 (Fig. 2) which permit the entry therein of those parts of the inlet valve which project above the level of the walls 24, 25 and 26.

In order to permit the compressed fluid or air to pass around the closure 51, when it is unseated, I make the section of this closure different from that of the bore 59; for example, this closure can be made from flat sided stock, such as square or hexagon. In the present instance, a hexagonal shape is shown, the diagonal thereof being substantially the same as the diameter of bore 50. In this way the closure 51 is well guided in its movement, and yet there are a number of passageways for the compressed fluid between the bore and the flat sides. Thus grooving or routing of the closure is obviated. These passageways are large enough to permit rapid movement of the compressed fluid.

I claim:

1. In a valve structure for a multiple cylinder fluid compressor, a separable valve supporting structure arranged to overlie the cylinders, said structure having a wall dividing it into an inlet and an outlet compartment, inlet and outlet valves respectively in said compartments, and a fluid tight cover sealing said compartments and resting against the wall thereof.

2. In a valve structure for a multiple cylinder fluid compressor, a separable valve structure arranged to overlie the cylinders, said structure being divided into an inlet and an outlet compartment, inlet and outlet valves respectively in said compartments, a fluid tight cover sealing said compartments, and means forming a screened inlet opening for the inlet compartment, supported on the structure.

3. In a valve structure for a multiple cylinder fluid compressor, a separable valve plate arranged to overlie the cylinder, said plate

being divided into an inlet and an outlet compartment, inlet and outlet valves respectively in said compartments, and a fluid tight cover sealing said compartments, said cover having one or more radiating fins.

5 In testimony whereof I have hereunto set my hand.

WILLIAM C. ALLEN.
